CLAIM

The ornamental design for a lid, as shown and described.

DESCRIPTION

FIG. 1 is a top perspective view of a lid showing the claimed design in an environment in which it may be used; and, FIG. 2 is a top view thereof. The broken lines in the drawings depict environmental subject matter and form no part of the claimed design.

1 Claim, 2 Drawing Sheets

See application file for complete search history.

FIG. 1

FIG. 2
